UNITED STATES PATENT OFFICE

161,153

STOCKING

Hans J. Bambach, Philadelphia, Pa.

Application April 30, 1949, Serial No. 2,354

Term of patent 14 years

(Cl. D47—7)

To all whom it may concern:

Be it known that I, Hans J. Bambach, a citizen of the United States, residing at 926 East Haines Street, in the city and county of Philadelphia, Commonwealth of Pennsylvania, have invented a new, original, and ornamental Design for Stockings, of which the following is a specification, reference being had to the accompanying drawings, forming part thereof.

Fig. 1 is a side view of the stocking, showing my design.

Fig. 2 is a rear view of the lower portion of the stocking, showing my design, said stocking being on the foot of a wearer and the wearer standing on her toes.

The characteristic feature of the invention resides in the border which outlines and forms the configuration at the heel shown.

I claim:

The ornamental design for a stocking, substantially as shown and described.

HANS J. BAMBACH.
